UNITED STATES PATENT OFFICE

2,521,600

RENEWABLE CARTRIDGE FUSE

William J. Pflaum, Pittsburgh, Pa.

Application June 5, 1947, Serial No. 752,783

6 Claims. (Cl. 200—131)

1

This invention pertains to cartridge fuses and especially to such in which a fusible member is contained in a renewable unit.

Electric fuses of this type are carried by resilient contactors or clips holding the two knife blades of the fuse snugly, intended to contact substantially the whole of the flat side surfaces thereof for causing the least resistance to the flow of the electric current. As the knife clips are mounted on blocks and lined up so that the corresponding operative clip surfaces are in the same plane it is of utmost importance that the knife blades of the fuses be perfectly aligned and securely held because only in such a case will the flat operative surfaces of the knives contact on their entire area the knife clips and secure thus best electrical conduction with the least heat development and loss of energy.

As the two knife blades are separate pieces mounted to an insulating bridge bar and electrically connected by a fusible conductor, the whole being carried by an insulating casing, the proper alinement of the two knife blades can be achieved only by employing structures that attach all parts of the fuse mechanically rigidly together and prevent the development of excessive stresses which could cause damage to the casing of the fuse or to its bridge bar portion when the fusible part is burned out by an electrical overload.

The fuses known up to date did not establish such optimum conditions because they permitted relative displacement between the parts of the fuse in case of variations in their temperatures, hence they did not fully prevent the knife blades from getting out of alignment or becoming distorted and thus from losing efficiency under exacting operating conditions.

My invention obviates these and other disadvantages by providing a fuse in which all stressed parts are mechanically rigidly connected to each other and which is so constructed that it prevents the development of excessive stresses in the non-fusible parts even in case that the fusible part is burned out by an electrical overload.

Hence one of the objects of my invention is to provide a renewable cartridge fuse the coacting parts of which are mechanically rigidly connected to each other.

Another object of the invention is to create a renewable cartridge fuse in which the cooperating structural parts are closely fitted together allowing only minute clearances between the coacting machined surfaces thereby constituting gas-passages of peripheral annular cross section-

2

al areas with relatively large bounding surfaces.

Still another object of the invention is to provide a device of the character described in which the knife blades are axially and angularly rigidly connected to the insulating bridge and to the insulating casing as well, by attachment means and connector means, respectively, that prevent any relative displacement axially, laterally or angularly between the parts by positive interference.

Another object of the invention is to provide a renewable fuse in which the linear, thermal expansion or contraction of the casing and of the portion of the renewable unit which is within the casing, is substantially the same.

Yet another object of the invention is to provide a renewable cartridge fuse which employs minute clearances of tortuous configurations for ventilation of the internal cavity of the casing for preventing the occurrence of excessive gas pressure, within the casing.

Another object of the invention is to provide a renewable cartridge fuse the internal cavity of which communicates with the atmosphere through minute passages of tortuous configurations and of relatively substantial lengths formed by mechanically rigidly connected metallic parts through which gases, generated within the casing by an electrical overload, will escape to the atmosphere at permissible pressure and cooled to a permissible temperature.

A further object of the invention is to provide a renewable fuse which has an improved electrical connection between the knife blades and the fusible element whereby the electrical resistance and with it the production of heat and waste of energy are substantially decreased.

Another object of the invention is to provide a device of the type set forth in which the attachment means between insulating bridge, knife blades and fusible element include a channel member having a web portion and flanges extending perpendicularly therefrom in both directions snugly embracing the side-, top- and bottom surfaces of the flat bar-shaped knife blades and those of the insulating bridge bar and also include an axially grooved cylindrical member with threaded extensions of reduced diameter at both ends thereof pressed through and peened into the knife blades and the channel members and being provided on each extension with a suitable nut for rigidly attaching the fusible member and the bridge bar, respectively, to the knife blades.

Yet another object of the invention is to provide a renewable cartridge fuse in which the in-

ulating casing is subjected to a predetermined tensile force and the insulating bridge bar to an equal compressive force, the latter being the reaction of the former and the structure is such that temperature variations will not substantially affect these forces which remain substantially constant under all thermal conditions.

Further objects of this invention are to provide a device of the class set forth which is simple in its construction and arrangement, durable and efficient in its use and inexpensive to manufacture.

The accomplishment of these and other objects by my invention will be clearly evident to those versed in the art when reading the following specification and perusing the accompanying drawing in which:

Figure 1 is a fragmentary, longitudinal cross-sectional view of the device in accordance with my invention, shown partly in outline.

Figure 2 is a radial cross sectional view on line 2—2 in Figure 1.

Figure 3 is a side elevational view of the knife blades and their connecting parts detached from the casing.

Figure 4 is an exploded view of the knife blade assembly shown in Figure 3.

Figure 5 is a perspective view of a modified form of the stud as used in Figures 1 to 4.

Figure 6 is a fragmentary sectional view of the knife blade assembly, partly in outline, showing the stud shown in Figure 5 in position.

Figure 7 is a perspective view of one of the terminal discs as used in this invention.

Figure 8 is a perspective view, slightly reduced, of one of the knife blade ends showing the channel member and the inner disc securely held in position on the knife blade by a stud.

Referring now to the drawing and especially to Figures 1 to 6 inclusive, illustrating the preferred embodiment, 10 represents a tubular casing of electrically non conductive material (such as hard fibre or other suitable material) to which ferrules 11, one at each end of the casing, are rigidly attached by means of rivets 12, shown, or otherwise. Ferrules 11 have threaded end portions 13 upon which preferably ring-shaped cap-nuts 14 are screwed. These cap-nuts 14 are for hand operation for which purpose their outer cylindrical surfaces are knurled. Cap-nuts 14 are also provided with an end bore 15, an adjoining cylindrical inner portion of greater diameter 16, and an internal threaded portion 17 that coacts with threaded end portion 13 of ferrules 11.

18 represents a terminal disc which loosely fits in bore 16 of cap-nut 14 and is retained therein by the shoulder 21 formed between the smaller end bore 15 and the larger cylindrical inner portion 16.

Each terminal disc 18 is provided with an elongated aperture 19 (see Figure 7) which slidably fits the knife blade 20 that protrudes outwardly through it. Each of said knife blades 20 has a shoulder 22 inward of which the knife blade is narrowed forming tang 23. In alignment with shoulder 22 is inner disc 25 which has a suitable elongated aperture for snugly admitting the tang 23 of knife blade 20.

It will be noted that the end portion 24 of channel member 27, when secured in position by driving the fluted stud 28 through the prepared apertures through the narrow portion 23 of knife blade 20 and said channel member 27, will force the inner disc 25 against the shoulder 22 of the knife blade 20 and thus retain the inner

disc 25 in fixed position without peening blade 23 around aperture of disc 25, which is usually done.

Tightly abutting the disks 25 is a bridge bar 26 which may be preferably from the same electrically insulating material as casing 10 or from a different one which, however, has substantially the same coefficient of thermal expansion. Between the tangs 23 of knife blades 20 and bridge bar 26 is the channel member 27 having a web portion 33 and perpendicularly thereto flange portions 34 which extend therefrom in both directions and hug snugly tang 23 on one side and bridge 26 on the other at their respective wide and narrow side surfaces.

Web 33 of channel member 27 is provided at its center with hole 41 of suitable diameter that coacts with properly located similar hole 42 in the tang to receive grooved portion of stud 28 that is pressed into both holes. Holes 41 and 42 have somewhat smaller diameter than the edges or teeth formed by the grooves so that the latter penetrate into the material surrounding the holes and an electrically and mechanically intimate connection results between stud, tang and channel member positively resisting relative angular displacement therebetween. It will be noted that flange portions 34 are symmetrical to the longitudinal and transversal cross sectional central planes of the web intersecting at the center of hole 41. The result of this symmetrical arrangement is that the flanges contact the tang and bridge bar at the same distance on both sides of stud 28 resisting most effectively rotary forces. Hence the connection by each stud and channel member makes the structure rigid without relying on the other stud and other channel member; furthermore the web 33 being abutted over its entire area by the adjoining tang the web is relieved from bending stresses.

The above mentioned grooved studs 28 have a cylindrical middle portion 35 of relatively large diameter provided with axially running grooves 36 and having at both ends threaded axial extensions of reduced diameter indicated by the numeral 29, coacting with nuts 30. After the cylindrical middle portion 35 of stud 28 is pressed through tang 23 and through channel member 27 it is peened from both sides forming an annular peening groove 36 and the corresponding outwardly conical enlargement of the grooved cylinder rigidly connecting tang 23 and channel member 27 and through extensions 29 and nuts 30 also bridge bar 26 which are thus transformed into a rigid unit. Mounting washers 31, fuse link 32 on extensions 29 and tightening nuts 30, a rigid mechanical- and excellent electrical connection is established between the two spaced apart knife blades 20. The inner disc 25, rigidly held against the shoulder 22 of knife blade 20 by the channel member 27, completes the rigid renewable unit the axial length of which between the inner discs is denoted by C.

At this time I wish to mention that one of the main features of my invention is the method of assembling the channel member 27 to the tang 23 of the knife blade 20, so that said channel member 27 also retains rigidly the inner disc 25 against the shoulder 22 of the knife blade 20, all by means of the grooved stud 28 provided with threaded extensions 29, the latter of which serving to securely hold one end of the fuse link 32 and one end of the bridge bar 26 by nuts 30. In other words, the grooved studs 28 serve a triple purpose; first, to permanently secure the channel member 27 to tang 23 of knife blade 20; second, to permanently and securely retain the inner

disc 25 against the shoulder 22 of knife blade 20 without peening the tang as is conventionally done and third, to removably fasten the bridge 26 and the fuse link 32 in rigid and aligned position to threaded stud extensions 29 by nuts 30.

As it is shown in figure 1 the axial length of the casing 10 including the attached ferrules 11 is denoted by B which is somewhat less than C. It will be also noted that the length of the threaded portion 13 of ferrule 11 is greater than that of the inner threaded portion 17 of cap-nuts 14. Consequently mounting the assembled renewable unit and terminal discs 18 is the casing by screwing cap-nuts 14 upon ferrule 11 there will be a gap between each ferrule and cap-nut and the screws will tend to elongate the casing 10 imparting to it through rivets 12 a predetermined tensile force acting axially. The same time bridge 26 will be compressed through discs 18 and 25 by force equal to that which tensions casing 10 as the former force is the reaction of the latter and the whole fuse is held axially and radially rigidly together as a unit or as one piece.

The device operates as follows:

The renewable unit having axial length C and bounded by inner discs 25 from which knife blades 20 protrude exactly aligned in both directions, is inserted into casing 10 upon which ferrules 11 are mounted rigidly. The discs 25 slidely loosely engaged the inner surface of ferrules 11 and aline the renewable unit coaxially in the casing 10. Discs 25 will somewhat protrude from ferrules 11 and they are preferably so set that the protrusions should be equal on both sides amounting to

$$\frac{C-B}{2}$$

however an unequal distribution of the protrusions will do no harm. Terminal discs 18 are now slipped over the knife blades 20 into contact with inner discs 25 and finally cap-nuts 14 are screwed on the threaded portion 13 of ferrules 11 sufficiently tight to complete the assembly to one rigid unit.

It will be noted that the length A of the casing between the rivets 12 is approximately equal with that of the bridge portion extending between the centers of the fluted studs 28, furthermore, that the length D of the peripheric metallic parts (ferrule 11 and cap-nut 14 measured from rivets 12 to the end of disk 25) is approximately equal with that of the knife blade portion between shoulder 22 and the center of stud 28. As the metallic parts and insulator parts on the casing as well as in the central renewable portion of the fuse have the same axial length and substantially the same coefficients of thermal expansion there will be no relative displacement or distortion because of change of temperature due to electrical overload, burning out of the fuse and possible arc formation, as the fuse will axially elongate and contract respectively as one whole piece in response to temperature variations.

The gases developing from combustion and arc formation will pass into the atmosphere exclusively through the tortuous path of minute widths constituted by the small clearances of the sliding fit between the inner surfaces of ferrules 11 and the peripheral surfaces of inner discs 25, continued by that established by surface roughness of discs 18 and 25, connected to the atmosphere by the sliding fit clearance between the knife blades 20 and apertures 19 in terminal discs 18.

The structural parts, forming this tortuous and

relatively long path of internal pressure relief, are all metallic, hence the escaping gases will be effectively cooled and an ignition by them of combustible matter outside of the fuse casing will be prevented. Hence the initial axially and radially rigid mounting of all the parts of the fuse will be maintained throughout, due to the avoidance of relative displacement between the casing and renewable unit, consequently the knife blades will not be thrown out of their exact alignment but will always contact the clips or prongs by which they are held on their full contact areas. As a result, the effectiveness of the fuse will be maintained and an increase of resistance, overheating and waste of electrical energy avoided.

Figures 5 and 6 show a second embodiment of my invention which is substantially the same as the first embodiment with the exception that a greater air space 37 between the fuse link 32 and the bridge bar 26 is created (Figure 6) by providing a reduced extension 38 at one end of the grooved portion of the stud 39 as shown in Fig. 5.

In order to replace the fusible link 32 it is only required to unscrew one of the cap-nuts from casing 10, after which the complete fuse assembly 25 may be withdrawn. Subsequently the nuts 30, which hold the fuse in position, are loosened enough to release the ends of the fusible link and a new one is slipped around the threaded extensions 29 of studs 28 or 39 and the nuts are tightened again.

In some cases, it is necessary to replace the bridge bar 26, this being readily accomplished by removing the nuts 30 from the threaded stud extensions 29, after which the new bridge bar with stud and channel member is put in place and fastened with the nuts 30.

Since one of the cap-nuts 14 and one of the terminal discs 18 have not been removed from the casing while replacing a new fusible link 32 it is now only required to insert one of the knife blade ends 20 of the removable fuse link assembly through the elongated slot 19 of said terminal disc 18 after which the other terminal disc 18 is slipped over the free end of the knife blade assembly and the cap-nut 14 is again screwed home into its normal position.

No tools other than a wrench or a pair of pliers are required to replace a fuse in the device.

From the above description it will be seen that each of the knives is part of a compact unseparable unit, that is, the knife blade 20, the channel member 27, the inner disc 25 and the grooved stud 28 or 39. The separable parts in the fusible link assembly are the fusible link, the bridge bar, and of course, the nuts which hold the link and the bridge in position.

Having fully described my invention and illustrated preferred embodiments thereof it will be understood that various changes and modifications may be made in the combined structures by those versed in the art without departing from the spirit of my invention, hence I do not intend to be limited by these exemplary embodiments, but what I claim as new and wish to secure by Letters Patent is:

1. A cartridge fuse comprising an electrically insulating tubular casing, attachment means for detachably but rigidly connecting thereto a renewable fuse unit composed of two, shouldered, outwardly wider knife blades extending axially in opposite directions from said casing symmetrically disposed to an axial central plane thereof, an elongated bridge bar of electrical insulating material overlappingly separating said blades, a

metallic link fusible by predetermined electrical overload connecting said knife blades, a metallic inner disc seated against the shoulder of each of said blades, a metallic terminal disc seated on each of said blades between said inner discs and said attachment means, metallic connector means rigidly fixing said knife blades to said bridge bar and retaining said fusible link, said connector means for each of said blades including a stud having an axially grooved cylindrical body and threaded extensions with nuts thereon, a channel member having a web with a centrally located hole for seating said grooved body and flange portions protruding perpendicularly from said web which is adapted to be interposed between the overlapping portions of said bridge bar and blade snugly clamping them, whereby said connector means prevent angular displacement between said bridge bar and said blade without subjecting said web to bending.

2. A cartridge fuse comprising an electrically insulating tubular casing, attachment means for detachably but rigidly connecting thereto a renewable fuse unit composed of two, shouldered outwardly wider knife blades extending axially in opposite directions from said casing symmetrically disposed to an axial-central plane thereof, an elongated bridge bar of electrically insulating material overlappingly separating said blades, a metallic link fusible by predetermined electrical overload connecting said knife blades, a metallic inner disc seated against the shoulders of each of said knife blades, a metallic terminal disc seated on each of said blades between said inner discs and said attachment means, metallic connector means rigidly fixing said knife blades to said bridge bar and retaining said fusible link, said connector means for each of said blades comprising a stud having an axially grooved cylindrical body and threaded extensions with nuts thereon, a channel member with a quadrangular web carrying a centrally located hole coacting with suitable holes in said bridge bar and said blade for force seating the grooved body in said blade and web and flanged portions protruding perpendicularly on both sides of said web which is adapted to be interposed in its entirely between the overlapping portions of said bridge bar and blade so the web and the flanges contact snugly one side and at least one edge of each of said bar and said blade, whereby angular displacement between said bridge bar and said blade is prevented without subjecting said web to bending.

3. A cartridge fuse comprising an electrically insulating tubular casing, attachment means for detachably but rigidly connecting thereto a renewable fuse unit composed of two shouldered outwardly wider knife blades extending axially in opposite directions from said casing symmetrically disposed to an axial central plane thereof, an elongated bridge bar of electrically insulating material overlappingly separating said blades, a metallic link fusible by predetermined electrical overload connecting said knife blades, a metallic inner disc having a central aperture corresponding to the cross-section of the narrower portion of said blades seated against the shoulder of each of said blades, a metallic terminal disc having a central aperture corresponding to the cross-section of the wider portion of said blades seated on each of said blades between said inner discs and said attachment means, metallic connector means rigidly connecting said knife blades to said bridge bar and retaining said fusible link, said connector means for each of said blades

comprising a stud having an axially grooved cylindrical body and threaded extensions with nuts thereon, a channel member having a quadrangular web carrying a centrally located hole coacting with corresponding holes in the bridge bar and blade for force-seating the grooved body in said blade and web, flange portions on opposite sides of the web extending substantially perpendicular to the plane of the web, said channel member being adapted to be interposed between the overlapping portions of the bridge bar and blade, said web being in contact over substantially its entire surfaces with the blade and bar and said flange portions being in contact with the edges of said bar and blade whereby the connector means prevent angular displacement between said bridge bar and said blade without subjecting said web to bending.

4. A cartridge fuse comprising an electrically insulating tubular casing, attachment means including a ferrule rigidly fixed to each end portion of said casing for detachably but rigidly connecting thereto a renewable fuse unit composed of two shouldered outwardly wider knife blades extending axially in opposite directions from said casing symmetrically disposed to an axial central plane thereof, an elongated bridge bar of electrically insulating material overlappingly separating said blades, a metallic link fusible by predetermined electrical overload connecting said blades, a metallic inner disc having a central aperture corresponding to the cross-section of the narrow portion of said blades seated against the shoulder of each of said blades, a metallic terminal disc having a central aperture corresponding to the cross-section of the wider portion of said blades seated on each of said blades between said inner disc and said attachment means, metallic connector means rigidly connecting said knife blades to said bridge bar and retaining said fusible link, said connector means for each of said blades comprising a stud having an axially grooved cylindrical body and threaded extensions with nuts thereon, a channel member having a quadrangular web portion carrying a centrally located hole coacting with corresponding holes in said bridge bar and blade for force-seating the grooved cylindrical stud body in said blade and web, symmetrically placed flange portions extending perpendicular to the body plane of the web on opposite sides thereof, said channel member being adapted to be interposed between the overlapping portions of said bridge bar and blade, said web portion being in contact with the bar and blade over substantially all of its surfaces and said flange members abutting the edges of the bridge bar and blade in tight engagement therewith whereby said connector means prevent angular displacement between said bridge bar and blade without subjecting said web to bending, said casing and ferrule on one hand and said component parts of said renewable fuse unit on the other hand having such axial dimensions and being made of such material that their thermal expansions at varying temperatures are relatively the same, whereby relative heat distortion between them is avoided incident to temperature variations said discs, blades, and attachment means forming with each other minute passages for the escape and cooling of gaseous matter expanding from the internal cavity of said casing to the atmosphere.

5. A cartridge fuse according to claim 3 in which said grooved cylindrical bodies, after forced insertion into said blades and channel members

respectively, are peened on both sides to expand their end portions outwardly whereby said blades, channel members and inner discs are converted into a rigid unit.

6. A cartridge fuse according to claim 3 in which said casing is subjected to a substantially constant predetermined tensile force and said bridge to a compressive force equal to said tensile force, said forces depending upon the force used at their assembly and being independent of the temperature variations.
